UNITED STATES PATENT OFFICE.

EMIL J. LONG, OF SAN FRANCISCO, CALIFORNIA, ASSIGNOR TO CONTINENTAL FURNITURE MANUFACTURING COMPANY, A CORPORATION OF CALIFORNIA.

UPHOLSTERING-MACHINE.

1,381,573.

Specification of Letters Patent. Patented June 14, 1921.

Application filed May 5, 1919. Serial No. 294,651.

To all whom it may concern:

Be it known that I, EMIL J. LONG, citizen of the United States, residing at San Francisco, in the county of San Francisco, State of California, have invented a new and useful Upholstering-Machine, of which the following is a specification in such full and clear terms as will enable those skilled in the art to construct and use the same.

10 This invention relates to a cushion stuffing machine and its object is to provide a machine whereby the hair, cotton or other material used for stuffing cushions may be placed therein in the proper position without wadding it into lumps, and also whereby a set of springs may be included within the cushion at the same time.

It will be understood by those skilled in the art that in producing cotton, hair or fiber filled cushions that it is very necessary to have the filling evenly and smoothly disposed within the cushion cover if the cushion is to be nicely shaped. In the present instance, this machine is for the purpose of permitting the assembling of the cushion materials in a heap slightly larger than the cushion itself, after which the materials are compressed into the machine sufficiently for the cushion cover to be placed thereover, whereupon the machine is withdrawn from the cushion, leaving the hair, cotton or fiber within the cushion cover and expanded against the same, and enough to produce a smooth, firm cushion.

35 A further object of the invention is to provide a machine which will be capable of stuffing seats, cushions, mattresses or other similar upholstered objects with the requisite amount of fibrous material, either springs, or of hair, cotton or other suitable fiber.

Other objects of the invention will appear as the description proceeds.

An embodiment of the invention is shown in the drawings in which the same reference numeral is applied to the same portion throughout, but I am aware that there may be modifications thereof.

In the drawings:

50 Figure 1 is a side elevation of the complete machine,

Fig. 2 is an end view of the complete machine looking from the left Fig. 1,

Fig. 3 is a plan view of the complete machine, and

Fig. 4 is a longitudinal sectional view of the machine.

The machine comprises a base 1 which is supported by four suitably heavy tubular posts 2, 3, 4, and 5, the posts having floor flanges 6, and transverse tubes 7 for making the structure more rigid.

The base is also connected with the posts by means of suitable flanges 8.

Above the base 1 and connected thereto by means of suitable floor flanges 9 are four posts 10 to 13 inclusive, said posts being connected with pipe fittings known as T's 15 to 18 inclusive. Pipes 19 and 20 are slideable in the T's 16, 17, and 15, 18 respectively, and these two pipes are in turn connected to a cross bar 21. The bar 21 has the threaded bar 26 screwed thereinto with sufficient pressure to prevent it from rotating during the operation of the clutch member 29.

The base 1 is provided with a subsidiary base 23 which has two posts carrying guides 24, 25, through which the screw 26 may slide. The guide 24 supports a tubular slide 28, while the guide 25 supports a tubular slide 27.

Threaded on the screw 26 there is a clutch member 29, and it is mounted between the ends of the two tubular guides 27, 28 so that it cannot move longitudinally with respect to the screw 26 unless it is rotated.

Loosely mounted upon the two tubular slides 27, 28 are two outer clutch members 30, 31, springs 32, 33 being used to hold the clutch members 30, 31 normally disengaged from the clutch member 29, with which either may be engaged when required, as will be later explained. The machine is driven by belt 70' and the cross belt 71' passing around the outside of the clutch members 30 and 31.

The angle of face of the clutch members 30, 31 and the opposite faces of the clutch member 29 is such that the clutch members 30 or 31 are engaged with the clutch member 29 that they will remain so engaged until a suitable force is applied thereto to disengage them. The object of this is to produce an apparatus which will automatically disengage the driving power from the

threaded nut clutch member 29 as soon as the beam 21 reaches either end of its throw.

Each of the clutch members has a boss against which bear thrust collars 34, 35 which boss is moved longitudinally with respect to the screw 26 by means of the levers 36, 37. The levers 36, 37 are mounted under the guides 24, 25 and below the screw 26, and they are operated to throw either 10 of the clutch members into engagement with the clutch member 29 at the will of the operator by means of the levers 38, 39. These two levers are in turn operated by pedals 40, 41 connected with rods 42 and 43. The 15 foot pedals 40, 41 are pivotally mounted on a floor bracket 44 below the cushion making hopper and in convenient reach for the feet of the operator. The levers 38 and 39 are so shaped that when either of the levers 38 20 or 39 are moved they will cause the engagement of one or the other sides of the clutch members 30, 31, and when so engaged, the screw 26 will be either extended or reversed in direction of longitudinal travel by reason 25 of the direction of rotation of the clutch member 29.

The cross bar 21 carried by the two tubes 19 and 20 has two slides 70, 71 therein, the position of which slides is determined by 30 the rotation of the screw 72. Said screw is operated by the hand wheel 73. The two slides 70, 71 have end members 72', 72'' and bottom members 73', 73'' secured thereto. When the machine is to be used, the box 35 formed by the ends 72', 72'' and by the bottom members 73', 73'' and top members 74, 74' form an inclosure open at one end in which the cushion stuffing material is first assembled. The bottom of the box consists 40 of the two pieces 73', 73'' while the top of the box consists of the two pieces 74, 74' slidable one over the other in pairs. They are each of such width as to permit substantially the whole of the beam 21 to 45 be used when desired. The members 74, 74' are hinged at the corners 75, 76 to the end members 72', 72''.

Since the material with which the cushion stuffing box is made is comparatively thin, 50 the beam 21 is provided with a rigid arm 46 which supports the bottom of the cushion stuffing box at its center, and with a hinged arm 47 which holds the top of the cushion stuffing box down when the two members 55 74, 74' are folded over upon the top of the material in the box. The arm 47 is pivoted at 48 on the cross beam 21. The arm 47 has a heel piece 49 which bears upon a block 50 carried by a spring 51 to secure 60 the arm 47 in the position shown in Fig. 4. When in this position, the block 50 bears upon a lug 52 carried by the cross beam 21 and holds the arm 47 down. To release the arm 47, there is a handle 53 which has a 65 portion 54 behind the spring 51, so that

upon moving the lever 53 to the left Fig. 4, the block 50 will be released from the heel piece 49 and permit the arm 47 to be raised out of contact with the top members 74, 74'. The guide 24 has two lugs 55, 56 at the sides 70 thereof, which guides support two rods 57, 58. Said rods extend through the cross beam 21 and terminate in a pusher bar 59, said pusher bar being for the purpose of pushing the filling within the stuffing box 75 in the cushion.

The slides 70, 71 are movable along the cross beam 21 and are held in a fixed position with respect thereto by means of the right and left threads on the screw 72, said 80 screw being operated by means of the hand wheel 73.

Mounted upon the screw 26 are two clamps 60, 61 which are held in a fixed position on said screw by means of the two split 85 clamps 60', 61' and the tightening bolts 62, 63. These clamps have heel pieces 64, 65 which are adapted to contact with the levers 36, 37 respectively to disengage the clutches, as will be later explained.

The operation of the apparatus is as follows: The workman opens the stuffing box by raising the arm 47 and by raising the top members 74, 74'. He then separates the sides of the box so that it is somewhat 95 wider than the cushion to be formed, and fills it with the hair, cotton or other fiber or material with which the cushion is to be stuffed. When the proper amount of filling has been placed in the box, the top 100 pieces 74, 74' are closed down upon the cushion filling, and the arm 47 is then pushed down upon the top of said top members 74, 74' to hold them down. The screw 72 is then turned to narrow the material 105 within the stuffing box enough to permit the cushion cover to be slipped over the box. The cushion cover is then pushed over the box and the lever 38 is then operated to cause the belt 70' and member 31 to drive 110 the member 29, whereupon the beam 21 will be turned toward the stand 1. This will be continued until the guard 64 contacts with the lever 36; whereupon the clutch member 31 will be released from the 115 member 29 and the machine will stop.

The result of this is that the material within the stuffing box will be pushed out of the same by the pusher bar 59, and into the cushion cover which is held against the material by the workman. As soon as the machine stops, the made up cushion will be removed from it and the lever 39 may be operated to cause the box to slide out over the pusher rod 39 in preparation for the pro- 125 duction of another cushion.

In order to provide for the rapid operation of the machine, the stops 60, 61 and the pusher bar 59 are adjustable in position so that the amount of movement of the box for 130

holding the stuffing material is limited to the precise amount necessary for a given cushion.

Having thus described my invention, what I claim as new and desire to secure by Letters Patent of the United States is as follows, express reservation being made of permissible modifications.

1. An upholstering machine comprising an open ended extensible receptacle having overlapped hinged top members and overlapping bottom members, means to hold said receptacle closed, a pusher bar therein, and means to move the extensible receptacle so that the pusher bar therein will push material out of the receptacle and into a container placed over the receptacle.

2. An upholstering machine comprising a support, a pair of slidable arms thereon, an extensible receptacle having overlapping hinged top members and overlapping bottom members, means to hold the receptacle closed, means to increase or diminish the width of the receptacle, a pusher bar therein, and means to retract the receptacle to push materials therein, out of the same, and into a container placed over the receptacle.

3. An upholstering machine comprising a base having a pair of slidable arms, a cross bar connected with said arms, an extensible receptacle carried by said cross bar, means to increase or diminish the width of the receptacle, means to hold the receptacle closed, a fixed pusher bar within the receptacle, and means to reciprocate the receptacle to push materials therein, out of the same, and into a container placed over the receptacle.

4. An upholstering machine comprising a fixed base, slidable arms thereon, a cross bar connecting the arms, an extensible receptacle carried by the cross bar, means to increase or diminish the width of said receptacle, a fixed bar therein, means to move the receptacle in either direction, and means to automatically stop the movement of the receptacle at either end of its travel.

5. An upholstering machine comprising a fixed base, slidable arms carried thereby, a cross bar carried by said arms, an extensible receptacle carried by said cross bar, means to increase or diminish the width of said receptacle, means to hold the receptacle closed, a fixed pusher bar within the receptacle, a screw extending from the cross bar, a threaded clutch member through which the screw extends, and means to drive said threaded clutch member in either direction, at will, to cause the movement of the receptacle.

6. An upholstering machine comprising a base, slidable arms carried thereby, a cross bar connecting the arms, an extensible receptacle carried by the cross bar, means to increase or diminish the width of said receptacle, means to hold the receptacle closed, a fixed pusher bar within the receptacle, means to retract the receptacle so that materials therein will be pushed out of the same and into a container placed over the receptacle, and means to automatically stop the movement of the extensible receptacle.

In testimony whereof I have hereunto set my hand this 26th day of April, A. D. 1919.

EMIL J. LONG.
